UNITED STATES PATENT OFFICE

2,545,299

APPARATUS AND METHOD FOR HANDLING
CAPSULES.

Rex E. Moule, Worcester, Mass., assignor to Norton Company, Worcester, Mass., a corporation of Massachusetts

Application June 23, 1947, Serial No. 756,570

2 Claims. (Cl. 62—104)

1

This invention relates to an apparatus and a method for handling, setting and cooling capsules. It has for one object to provide a method and apparatus for use in connection with encapsulating machines which produce filled capsules. The capsules may be formed of gelatinous or other material and contain liquid or solid filling material. Such capsules, when formed, require special handling to prevent sticking together, breaking, marring or distortion, and it is one object of the invention to provide an apparatus and a method whereby the capsules, as formed, are deposited on a conveyor and are treated automatically and continuously so that they are "set" and cooled as made.

Other objects will appear from time to time throughout the specification and claims.

This invention is illustrated more or less diagrammatically in the accompanying drawings, wherein:

Figure 1 is a plan view with parts broken away and parts omitted;

Figure 2 is a side elevation of the structure shown in Figure 1, with parts omitted and parts broken away;

Figure 3 is a section illustrating a modified form of the device;

Figure 4 is a transverse section taken at line 4—4 of Figure 3;

Figure 5 is a fragmentary plan view of the conveying apron;

Like parts are indicated by like characters throughout the specification and the drawings.

In the form shown in Figures 1 and 2, a pair of tanks 1, 1 is provided and heat exchangers such as cooling coils or other cooling means 2, 2 are arranged within the tanks 1. Cooling or refrigerating fluid reaches the coils 2 through a pipe system which includes the pipes 3. The invention is not limited to any particular cooling or refrigerating means and any suitable coolant or refrigerant may be used.

Baskets 4 of suitable size and strength are arranged to fit into the tanks. They may be provided with strengthening edge members 5. The baskets are of such depth that when in position within the tanks 1 their bottoms are below the level of liquid in the tanks.

One or more draining trays or drainboards 6 with raised edges 7 are associated with the tank system and each draining tray is provided with a spout or drain conduit member 8 arranged to return liquid to one or another of the tanks 1. If desired, the trays 6, 6 may be made as a unit and separated from each other by a mem-

ber 9. These trays may be made as a single unit without the separator 9. Suitable supports 10, 10 are provided for the trays and the tanks may be supported in any manner desired.

5 In the modified form of Figures 3, 4 and 5, continuous means for receiving, treating and discharging the capsules are provided. The mechanism of the last three figures includes one or more tanks 11 carried on supports 12, or otherwise supported. Associated with the tank is an inclined drainboard, draining table or shelf 13 which is provided with a raised edge or border 14. Positioned within the tank is a pair of tracks 15 and baffling members 16 are preferably also provided within the tank. These baffling members extend, as shown in Figure 4, inwardly to mask or overlie the tracks 15.

A conveyor which includes a pair of chains 17 is provided with rollers 18. The rollers operate in and are guided by the track 15. A screen or other perforated member 19 is supported upon the chains 17 and may be further supported by transverse stiffening members 20 which extend from one chain to the other.

20 25 At each end the chain 17 is engaged upon sprockets 21 which are supported on shafts 22 in bearings 23. The sprockets are notched or otherwise shaped, as at 24, to engage the rollers or, if desired, to engage the chain links or the transverse members 20. One of the sprockets may be carried on a support 25 and the other may be carried on a support 26 which is itself supported on the tank 11. A box or container 27 may be provided to receive the capsules 28 as they are discharged from the container.

In both forms of the invention the tank or tanks contain a liquid which is preferably cool. One suitable cooling liquid is kerosene, and the capsules as formed are deposited or dropped directly from the machine which forms them into the tanks 1 or the tank 11. The capsules thus are immediately after formation immersed in a liquid which prevents their sticking together and prevents damage or breaking of the capsules.

40 45 The invention is not limited to the use of any particular liquid in the treatment of the capsules. They may be treated in one liquid after another. For some purposes naphtha might be used, but it evaporates too rapidly for economical use. Carbon tetrachloride is useful but tends to be injurious to workers. Kerosene is mentioned merely as one of many different liquids into which the capsules may be deposited as they are formed.

50 Other hydrocarbons are suitable in addition to

2

kerosene. In some cases after the capsules have been cooled in the hydrocarbon fluid they must be subsequently washed with naphtha.

Although I have shown an operative form of my invention, it will be recognized that many changes in the form, shape and arrangement of parts can be made without departing from the spirit of the invention, and my showing is, therefore, to be taken as, in a sense, diagrammatic.

The use and operation of this invention are as follows:

In the form of Figures 1 and 2 the capsules are preferably dropped directly into the tanks 1 as they are formed. They may fall directly from the capsulating machine. Since the baskets are below the level of the liquid within the tanks 1, the capsules fall first into the liquid and as they sink through it, they come to rest on the baskets. They then may be removed from time to time by lifting the basket out and depositing the basket on the tray or shelf 6. While the basket is resting on the tray 6 the kerosene or other liquid is free to flow away from the capsules through the basket and onto the trays. It then may be returned by the spouts or guides 8 to the tanks. The capsules, after cooling in the liquid within the tank, may be washed, dried, sorted and packed. The particular apparatus shown and the method disclosed are not limited to any definite after treatment or after use of the capsules after they leave the mechanism.

In the modified form of Figures 3, 4 and 5 the capsules are deposited into the liquid and sink downwardly through it and are picked up by the moving conveyor screen 19. The size of the tank 11 and the speed of the conveyor are such that the capsules have been properly set, cooled and cleaned before they are lifted from the liquid by the conveyor. They then move over the tray or shelf 13 and the kerosene or other liquid in which they have been treated drains from them and returns downwardly along the inclined tray 13 and is returned to the tank 11. Finally, as the conveyor continues to move the capsules fall from it and are deposited in the container or box 27 from which they may be removed when desired for drying.

While kerosene has been mentioned as a suitable treating liquid, the invention is not limited to that material. Almost any cool liquid will produce a beneficial result, because it cushions the fall of the capsules and prevents their striking directly upon each other. As they sink through the liquid their speed is arrested so that they do not come violently in contact with each other as they are collected either in the baskets 4 or on the conveyor 19. Kerosene is merely one of a variety of suitable liquids for receiving the capsules as they are formed. It prevents their sticking together.

The step of dropping the newly formed cap-

sules into a cooling fluid is important because it prevents them from sticking together and it also tends to cool the capsule and particularly the hot seam formed about the periphery of the capsule in its gelatin shell. If this is not cooled promptly, experience has shown that pressure inside the capsule may pull the seam apart somewhat, making it weak or in some extreme cases actually breaking it. It is important that this seam be not weakened or broken because after the capsule has been shipped, any weakness at the seam may develop into a leaking capsule in the field, and dropping the capsules into a proper cooling fluid as soon as they are made tends to prevent this. Furthermore, if a capsule does break after it is formed, the liquid of the bath prevents the released filling material of the broken capsule from contaminating other capsules.

I claim:

1. Apparatus for treating capsules of the type comprising a filling enclosed in a shell of soft capsule-shell-forming material after their formation by a capsulating machine, comprising a tank 25 for a liquid bath, said tank being open at its top so that capsules discharged from a capsulating machine may drop directly into the bath, a heat exchanger for maintaining the liquid in the tank cool, a basket in the tank for carrying capsules 30 immersed in the bath, said basket being movable into and out of the tank, and a drainboard leading to the tank for returning liquid drained from the capsules back to the tank when the basket is moved out of the tank.

2. Apparatus for treating capsules of the type comprising a filling enclosed in a shell of soft capsule-shell-forming material, such as gelatin, after their formation by a capsulating machine, comprising a tank for a liquid bath, said tank being open at its top so that capsules discharged from a capsulating machine may drop directly into the bath, a heat exchanger for maintaining the liquid in the tank cool, a basket removably carried in the tank for receiving capsules and carrying them immersed in the bath, and a drainboard toward one side of the tank draining into the tank for supporting the basket upon its removal from the tank to permit liquid to drain from the capsules in the basket back into the tank.
